CLAIM

The ornamental design of a body sensor, as shown and described.

DESCRIPTION

FIG. 1 is a front isometric view of the body sensor,
FIG. 2 is a rear isometric view of the body sensor,
FIG. 3 is a front view of the body sensor,
FIG. 4 is a rear view of the body sensor,
FIG. 5 is a left-side view of the body sensor,
FIG. 6 is a right-side view of the body sensor,
FIG. 7 is a top view of the body sensor; and,
FIG. 8 is a bottom view of the body sensor.

1 Claim, 8 Drawing Sheets
